UNITED STATES PATENT OFFICE.

LEWIS SMITH, OF WAYNE CITY, ILLINOIS.

MONUMENT MOLD.

Application filed March 7, 1925. Serial No. 13,853.

To all whom it may concern:

Be it known that I, LEWIS SMITH, a citizen of the United States, residing at Wayne City, in the county of Wayne and State of Illinois, have invented certain new and useful Improvements in Monument Molds, of which the following is a specification.

This invention relates to monument molds, and has more particular reference to 10 an apparatus for molding concrete monuments in the form of ornamental open rectangular enclosures adapted to border burial plots or the flower beds thereof.

The primary object of the invention is to 15 provide a molding apparatus which is extremely simple and durable in construction and capable of being readily used, without the requirement of special skill or the expenditure of unnecessary time or labor, for 20 the expeditious manufacture of concrete monuments of the above kind.

A further object is to provide improved 25 means for molding a rectangular concrete enclosure composed of integral end and side walls having ornamental depressions in the outer surfaces thereof.

Still another object is to provide an apparatus of the above kind embodying a main mold for integrally forming the walls of 30 the body of the monument and an auxiliary mold for forming solid ornamental corner blocks adapted to be disposed upon the upper edges of the walls at the corners of the body or the junctures of the walls thereof.

35 With the above general objects in view, and others that will become apparent as the nature of the invention is better understood, the same consists in the novel form, combination and arrangement of parts herein- 40 after more fully described, shown in the accompanying drawings and claimed.

In the drawings, wherein like reference characters represent corresponding parts throughout the several views,

45 Figure 1 is a top plan view, partly in section, of the main mold embodying the present invention, and illustrating the mold partly filled with concrete.

Figure 2 is a view partly in side elevation and partly in section on the line 2—2 of Figure 1.

Figure 3 is a transverse section taken substantially upon line 3—3 of Figure 1.

Figure 4 is a longitudinal section taken 55 substantially upon line 4—4 of Figure 1.

Figure 5 is a perspective view of the

monument formed by the main mold shown in Figure 1 and equipped with the corner blocks formed by the auxiliary mold.

Figure 6 is a fragmentary sectional view 60 taken upon line 6—6 of Figure 5.

Figure 7 is a front elevational view of the auxiliary mold with concrete therein, the mold being partly broken away and in section. 65

Figure 8 is a top plan view of the auxiliary mold and,

Figure 9 is a side elevational view thereof.

Referring more in detail to the drawings, and particularly to Figures 1 to 4 inclusive, 70 the main mold embodies inner and outer members or open frames of rectangular form. The outer frame is composed of separable similar side walls or boards 5 and similar end walls or boards 6. As shown, 75 the end walls 6 are adapted to flatly abut the ends of the side walls 5 when the latter are arranged in proper spaced parallel relation, and when the side walls are properly spaced, the ends of the end walls project 80 outwardly beyond the outer sides of said side walls. The ends of the end walls are formed with transverse openings 7 for reception of bolts 8 which are rigidly secured in pairs to the outer surfaces of the ends of 85 the side boards 5, and nuts 9 are threaded onto the outer ends of the bolts 8 at the outer sides of the end walls for drawing the end walls tightly against the side walls and detachably securing the several walls together to provide a strong rigid rectangular frame. 90

The inner frame consists of similar side walls 10 and similar end walls 11, and when the frame is set up, the end walls 11 are 95 disposed between the side walls 10 with the ends of said end walls 11 flatly abutting the side walls 10 as clearly shown in Figure 1. One end of each side wall is hinged as at 12 to the adjacent end of one end wall so that 100 the end walls may swing inwardly from their operative position wherein the same are disposed at right angles to the side walls. The end walls have sliding bolts 13 mounted on their inner surfaces, and these bolts are 105 arranged to enter openings 14 in the free ends of the side walls for releasably holding the end walls from swinging inwardly and thereby maintaining the frame in open or set up condition. 110

The inner frame is adapted to be positioned within the outer frame, and these

frames are of such relative size as to leave an endless space of uniform width between them for reception of the concrete or similar material to be molded, whereby an integral rectangular enclosure is formed as shown in Figure 5 composed of end walls 15 and side walls 16.

Projections 17 are provided on the inner surfaces of the wall members 5 and 6 of the outer frame of the mold for forming ornamental depressions or recesses 18 in the outer surfaces of the walls 15 and 16 of the molded monument or enclosure. The edges of these projections are beveled as shown for facilitating removal of said walls 5 and 6 from the molded article and for rendering the depressions 18 more ornamental and less liable to collect dirt. Also, the corners of the walls of the depressions 18 are thus rendered less liable to become chipped.

The auxiliary mold consists of two members, one member embodying a front wall 19 rigid with and at right angles to a side wall 20, and the other member embodying a rear wall 21 rigid with and at right angles to a side wall 22. The adjacent ends of the side wall 20 and the rear wall 21 are hinged together as at 23 so that an end edge of the rear wall 21 abuts the inner side of the side wall 20 when the free end edge of the front wall 19 abuts the inner side of the side wall 22, and whereby the molds may be opened for removal of the molded article by swinging the mold members apart. The walls of the mold members 19, 20 and 21 are of trapezoidal form and of such size as to cooperate for forming a block of truncated pyramidal form, the base of which is of the same width as that of the monument walls 15 and 16. Thus, a plurality of these blocks may be used, one at each corner of the molded enclosure, and upon the upper edges of the walls thereof as shown in Figure 5 for providing ornaments 24 which enhance the appearance of and complete the monument structure. The side walls 20 and 22 may carry hooks or keepers 25 having upwardly projecting ends behind which the ends of a locking strip or bar 26 may be engaged when disposed to extend across the front wall 19, whereby the members of the auxiliary mold may be releasably held in operative relation.

When the members of the main mold are set up as shown in Figure 1, the concrete is poured between said members and allowed to set and harden in the usual manner. When properly set and allowed to harden, the article may be removed by moving the nuts 9 from the bolts 8 and then sliding the end members or walls 6 off of the bolts 8 to allow removal of the side walls 5. The bolts 13 are then retracted so as to disengage from the openings 14, whereupon a member composed of one side wall 10 and one end wall 11 may be withdrawn upwardly for its removal. The other member may be more readily removed then by swinging the end wall 11 inwardly. The several walls may be placed in compact relation for shipment or storage, as is obvious by reason of the construction described.

The auxiliary mold is simply set up as shown in Figures 7 to 9 inclusive and the concrete poured therein while the mold rests upon a flat supporting plate or base, after which the bar 26 may be removed for permitting the members of the auxiliary mold to be swung apart, whereby the molded block or corner ornament 24 may be removed.

From the foregoing description it is believed the construction and operation as well as the advantages of the present invention will be readily understood and appreciated by those skilled in the art.

What I claim as new is:

A mold for forming a concrete monumental enclosure having integral walls, including inner and outer members adapted to be disposed in spaced concentric relation, the outer member comprising separable walls, and the inner member comprising side and end walls, one end of each end wall of the inner member being hinged to one end of one side wall of the inner member, said end walls of the inner member being disposed between the ends of the side walls thereof and being provided with sliding bolts, the free ends of the side walls of said inner member being formed with transverse openings for reception of said bolts to maintain the inner member in set up condition.

In testimony whereof I affix my signature.

LEWIS SMITH.
